ATOMIZER STOPPER FOR PHIALS

Jean Emmanuel Paul Tsouderos,
Saint-Maur-des-Fosses, FranceApplication October 24, 1950, Serial No. 191,754
In France October 25, 1949

10 Claims. (Cl. 299—88)

1

The present invention covers an atomizer stopper designed for mounting on a phial containing a liquid product to be atomized.

The purpose of the invention is to create such an atomizer stopper which offers a perfectly regular shape when it is in its closing position, completely hiding the atomizing device.

Another object of the invention is to create an atomizer stopper capable of being operated by depressing a cap sliding on a pump cylinder and of being locked in its lower position and extending a part in the shape of a sleeve, mounted on a socket, permanently secured to the neck of the phial in such a manner that the stopper appears with a perfectly continuous outer surface and an upper surface which can be completely smooth.

Another object of the invention is to create an atomizer stopper of the above type comprising a simple pump mechanism ensuring a perfect atomization of the liquid through a hole provided in a side wall of the stopper.

The invention also aims at means which are completely hidden for introducing air into the phial and into the pump body.

Various other objects and advantages of the invention will become apparent from the following detailed description.

Figure 1 is an elevational section of a first type of embodiment of an atomizer stopper according to the invention.

Figure 2 is an elevational section of a second type of embodiment.

Figure 3 is a partial schematic section along line III—III of Figure 2.

Figure 4 is an elevational section of a third type of embodiment.

Figure 5 is a partial schematic section along line V—V of Figure 4.

Figure 6 is an outside view of the atomizer stopper ready for operation.

Figure 7 is an outside view of the atomizer stopper, closed for transportation.

In Figure 1, the atomizer stopper consists of a part 1, offering a recess 2 at its lower portion; the edge of said recess is threaded inside. A recess 3 is provided in the upper portion of part 1; the edge of this recess is threaded inside. A central channel 4 is drilled in the center of part 1 and extended through a boss 5 placed at the center of the lower recess 2. 6 designates a horizontal channel drilled into part 1 and connecting the central channel 4 with a chamber 7 communicating with the outside through a horizontal channel 8. A short pipe 9 is screwed into a tapping provided in the upper portion of the cham-

2

ber 7; this pipe is bored, at its center, with a vertical channel 10 and on its side, with a small horizontal channel 11 placing the central vertical channel 10 in communication with the chamber 7. A socket 12, threaded outside, is permanently sealed with cement on the neck of the phial containing the product to be atomized. 13, 13a, 13b, designate grooves provided in the inner wall of the socket 12, facilitating the holding of the cement. This socket offers, on the outside, a vent which allows a communication between the inside of the phial on which it is secured and the outside, a hole being provided at the upper portion of the socket 12 which is screwed in the lower, recessed portion 2 of part 1. A stem 14 is screwed in the upper portion of the central tapped channel 4; said stem offers a flange 15 limiting its engagement into the channel 4. A pump cylinder 16 is screwed, at its lower portion, into the upper recess 3 of part 1. This pump cylinder offers, at its upper portion, a rectangular hole 17. A rectangular rod 18 can slide inside the rectangular hole 17 and offers, at its base, a turned down portion 19 on which is engaged a piston 20 comprising a metal plate 20, a leather part 21, and a cup shaped washer 22 holding the leather part 21, the assembly of these three parts being locked on the turned down portion 19 of the rod 18 by a nut 23 screwing into a screwthread provided on the turned down portion 19.

The rod 18 offers a second turned down portion at its top; a stud 24 is placed in this turned down portion. A cap 25 offers a boss 26 at its center. The rod 18 is bored, at its center, by a channel 27 which allows it to slide freely on the stem 14. The cap 25 is secured on the piston 18 by forcing it in the boss 26 into the channel 27; a helical spring 28 is placed in the pump cylinder 16. This spring bears, on one hand, on the bottom of the upper recess 3 of part 1, and, on the other hand, against the cup shaped washer 22 supporting the pump leather 21. 29, 30, designate the vent holes of the pump body; a capillary tube (not shown in the drawing), dips into the liquid to be atomized and is screwed by its upper portion in the central tapped channel 4.

The atomizer stopper operates in the following manner:

The socket 12 being sealed on to the neck of the phial containing the liquid to be atomized, the atomizer stopper, on which is mounted the capillary tube dipping into the liquid to be atomized is screwed thereon. Said liquid rises, due to capillarity, into the chamber 7, through the channels 4 and 6; then the cap 25 is depressed. The air

contained in the pump body 16 is expelled by the leather washer 21 into the channel 18 of pipe 9, then passes through the capillary channel 11 and from there into the chamber 7 where it atomizes part of the liquid it contains, the whole issuing towards the outside through the channel 8.

The cap 25 is released and comes back to its rest position under the action of the spring 28; air enters the pump body through the holes 29, 30, and the phial through the passage provided between the socket 12 and the edge of the lower recess 2 of part 1 then through the hole provided at the center of the socket 12. At the same time, some liquid fills the chamber 7. The atomizer is again ready to operate.

If it is desired to carry the phial provided with its atomizer stopper, the stopper 25 is pushed in, then imparted a rotation of a quarter turn for housing the upper edge 18a of the rod 18 under the upper portion of the pump body 16; the stud 24 limits the rotation of the cap; the whole then assumes the shape shown in Figure 7.

In Figure 2, the atomizer stopper is made up of a lower part 31, comprising an upper recessed portion 31a, the edge of which 31b is tapped and a recessed lower portion 31c.

The central portion 32 is provided with a tapered conical hole 33 connecting the upper recess 31a with the lower recess 31c. A part 34, the upper truncated conical portion 34a of which occupies the hole 33, comprises a lower cylindrical portion 34b, recessed, the inner edge 34c of which is tapped. The part 34 is bored, at its center, with a tapped channel 35 and two channels 36, 37; the channel 36 is extended by a channel 38 bored into the part 31 and opening into a chamber 38a, the edge of which 38b is tapped; a channel 38c extends the channel 38 and places the chamber 38a in communication with the outside. A pipe 39 is housed in the chamber 38a; this pipe is bored with a vertical channel 39a connected with the chamber 38a through a capillary channel 39b.

A socket 40, threaded outwardly, is sealed permanently with cement, on the neck of the phial containing the product to be atomized, 40a, 40b, 40c designate grooves provided in the inner wall of the socket 40, facilitating the holding of the cement. The socket 40 screws into the recessed, tapped portion 34b of part 34. A sealing gasket 41 is interposed between these two latter parts. Part 31 is bored with a blind hole 42 in which a spring 43 is housed, pressing against a ball 44 which is placed in two semi-spherical recesses 44a, 44b provided in part 34 (Figure 3). The function of this device will be explained later on.

A pump cylinder 45 is screwed on the tapped portion 31b of part 31; this pump cylinder contains a stem 46 screwed in the tapped channel 35 and offers a flange 46a holding a spring 47 which supports the part 34 inside the trunco-conical hole 23 bored at the center of the part 31. The upper portion 45a of the pump body, is bored with a rectangular hole 45b, through which can slide a rectangular rod 48, the lower portion of which is turned down and threaded, said portion receiving a metal disc 49, a leather washer 50 forming a piston and a cup shaped element 51 holding the leather. The assembly of said three parts is locked on the lower, turned down portion of the rod 48 by a nut 52; the upper portion 48b of the rod is also turned down and offers a stud 53, the function of which will be explained further on.

The rod 48, at its center, is provided with a

channel 48c, and can thus slide on the stem 46. A cap 54 offers at its center a boss 54a, forced into the upper portion of the channel 48c bored into the rod 48. This cap may completely surround the pump body 45. 55 designates a spring bearing, on one hand, against the bottom 31a of part 31, and, on the other hand, on the cup shaped element 51. This spring tends to push the rod 48 upwards, together with the leather washer 50 of the pump. 56, 56a designate the air vents of the pump. A capillary tube dipping into the liquid to be atomized contained in the phial on which the atomizer stopper is screwed is itself screwed by its upper portion into the tapped channel 35. 37 designates a screw preventing the stem 46 from rotating.

The atomizer stopper operates as follows:

The socket 40 being sealed on the neck of the phial containing the liquid to be atomized, the atomizer on which is mounted the capillary tube is screwed on it. The liquid rises, due to capillarity, up to the chamber 38a, going through the channels 36 and 38. The cap 54 is then depressed. The air contained in the pump body 45 is expelled by the leather washer 50 into the vertical channel 39a of the pipe 39, then passes through the capillary channel 39b into the chamber 38a, atomizing a certain amount of the liquid it contains; the atomized air and liquid mixture issues outwards through the channel 38c.

The cap 54 is released, and resumes its rest position under the action of the spring 55; some air enters the pump body through the holes 56, 56a and the phial through the passage provided between the parts 31 and 34, then through the channel 37 opening above the central hole provided in the socket 40. At the same time, some liquid fills the chamber 38a. The atomizer is again ready to operate.

If it is desired to carry the phial provided with its atomizer stopper, a rotation of one quarter turn, for instance, is given to part 31 with respect to part 34; the ball 44 then moves from one of the semi-spherical cavities to the other semi-spherical cavity (Figure 3). This motion is possible because the connection between the parts 31 and 34 is effected by the spring 47, which makes it flexible. Further, in view of the carrying of the phial, the cap 54 is pushed in, then given a rotation of a quarter turn, for instance, to house the edge 48d of the rod 48 under the upper portion 45a of the pump body 45. The stud 53 limits the rotation of the cap, and the whole then assumes the shape shown in Figure 6.

If it is desired to use the atomizer again, the above-mentioned operations should be effected in the reverse order.

The atomizer stopper of Figure 4 is comprised of a lower part 60, comprising an upper recessed portion 61, the edge of which 61a is tapped and a lower recessed portion 62. The central portion 63 is bored with a trunco-conical hole 64 connecting the upper recess 61 and the lower recess 62. A part 65, the upper trunco-conical portion of which 66 occupies the hole 64, comprises a lower cylindrical portion 67, recessed, the inner edge of which 68 is tapped. The part 65 is bored, at its center, with a tapped channel 69 and two channels 70, 71. The channel 70 is extended by a channel 72 bored into the part 60 and terminates into a flared portion 73, the edge of which 73a is tapped. The trunco-conical portion 63 of the part 60 is drilled with a channel 74, bent at a right angle, and placing the recessed portion 61 and the flared portion 73 in commun-

nication. A socket 75, threaded outwardly is permanently sealed by means of cement on the neck of the phial containing the product to be atomized. 76, 76a, 76b, designate grooves provided in the inner walls of the socket 75, facilitating the holding of the cement. The socket 75 screws into the recessed and tapped portion 67 of the part 65, a sealing gasket 77 is interposed between these two parts. A pipe 78, bored with a central channel 78a, is secured by being forced on the end of the channel 74 and an end part 79 is screwed in the tapping 78a of the flared portion 73; this end part is bored with a channel 79a.

Two studs, 80, 81, secured in the part 65 (Figure 15), act as stops for the stud 82, secured in the body of the part 60. The channel 74 is extended by a pipe 83. A pump body 84 is screwed on the tapped portion 61a of the part 68; this pump body contains a stem 85, screwed in the tapped channel 69 and offers a flange 86, holding in position a spring 87 supporting the part 65 inside the trunco-conical hole 64 of the part 68. The upper portion of the pump body 84 is bored with a rectangular hole 88, through which a rod 89 can slide, the lower portion of which is turned down and threaded, said portion receiving a metal disc 90, a leather washer 91 acting as a piston and a cup shaped element 92 holding the leather washer 91. The assembly of these three parts is locked on the turned down portion of the rod 89 by a nut 93. The upper portion of the rod 89 is turned down and offers a stud 94, the function of which will be explained later on.

The rod 89 is hollow and slides on the stem 85. A cap 95 offers at its center, a boss 96, forced on the upper portion of the stem 89. This cap may completely surround the pump body 84. 97 designates a spring bearing, on one hand, on the bottom of the recessed portion 61 of the part 60 and, on the other hand, on the cup shaped element 92. This spring pushes upwards the rod 89 and the leather washer 91 of the pump.

98, 99 are the air vents of the pump. A capillary tube (not shown in the drawing), dipping into the liquid to be atomized, is screwed by its upper portion into the tapped channel 69. The atomizer stopper operates as follows:

The socket 75 being sealed on the neck of the phial containing the liquid to be atomized, the atomizer, on which the capillary tube is mounted, is screwed on it. The liquid rises, due to capillarity, up to the flared portion 73, going through the channel 70. The cap 95 is then depressed; the air contained in the pump body 84 is expelled by the leather washer 91 into the channel 74, goes through the pipe 78 and thence to the end part 79, atomizing the liquid thus carried along during its passage through the flared portion 73.

The cap 95 is released and resumes its position of rest under the action of the spring 97; some air enters the pump body through the holes 98, 99 and the phial through the passage provided between the parts 60 and 65 and the channel 71. Some liquid again fills the flared portion 73. The atomizer is again ready for operation.

When it is desired to carry the phial provided with its atomizer stopper, a rotation of a quarter turn is imparted to the part 69, with respect to the part 65. The stud 82 then moves from the stud 80 to the stud 81 (Figure 5). This motion is possible since the connection between the parts 60 and 65 is effected by the spring 87, which makes it flexible. Further, in view of the carrying of the phial, the cap 95 is pushed in and is imparted a rotation of a quarter turn to house

the portion 89a of the rod 89 under the upper wall of the pump body 84. The stud 94 limits the rotation of the cap. The whole then assumes the shape shown in Figure 7.

When it is desired to again utilize the atomizer, the above-mentioned operations are effected in the reverse order.

The pipe 83 prevents the dust particles contained in the pump body and falling downwards, from moving down in the channel 74 and thence towards the flared portion 73.

Various modifications may be made to the types of embodiment given by way of examples, within the scope of the invention.

I claim:

1. An atomizer stopper for phials, comprising in combination a socket adapted to be sealed on the neck of the phial, a screw thread on the outside of said socket, a unit offering at its lower portion a tapped sleeve screwed on said screw thread, at its middle portion a plate and at its upper portion a second tapped sleeve, a central boss extending from the under side of the plate, a tapped hole extending through said boss and plate, for receiving a capillary tube dipping into the liquid, said plate having a first channel starting from said tapped hole and going to a chamber provided in the plate near its periphery, a short pipe placed inside said chamber and leaving at the lower portion of the chamber a space for receiving the liquid, said plate having a second channel communicating said chamber with the outside, said pipe having a hole facing said second channel, a pump body consisting of a cylindrical cup shaped element screwed by its lower threaded edge in said second tapped sleeve of said unit, a guiding rod screwed in the upper portion of the tapped hole of said plate and extending upwards inside said pump body, a piston placed inside the pump body, a piston rod secured to said piston, a bore inside said piston rod allowing it to slide on said guiding rod, a spring tending to push said piston towards the upper portion of the pump body, and a cylindrical cap secured to the upper portion of the piston rod of said piston, said cap sliding on the outside of the pump body and enclosing it completely when it is pushed downwards with the piston against the action of the spring, and means for immobilizing said cap in its downwardly pushed position.

2. An atomizer stopper according to claim 1, wherein said guiding rod has a flange for bearing on the upper side of the plate of said unit, limiting the extent of movement of said guiding rod into said tapped hole.

3. An atomizer stopper according to claim 1, characterized in that said piston comprises a plate element, a leather element bearing against said plate element and a cup shaped element holding the central portion of said leather element against said plate element, the piston rod having a turned down portion on which are stacked these piston elements, and a nut screwed on a threaded end of said turned down portion to ensure that the piston elements are held in position.

4. An atomizer stopper according to claim 1, wherein said socket has a channel extending along the vertical portion and the upper portion thereof to permit air to enter the phial on which it is sealed.

5. An atomizer stopper comprising, in combination, a socket adapted to be sealed on the neck of the phial, a unit including a sleeve screwed on said socket, a sealing gasket being pressed be-

tween the upper portion of the socket and the under side of the bottom of said sleeve, a central boss extending from the bottom of the sleeve, a tapped hole extending through said boss, said boss having a cone shaped surface, and a part offering a frusto-conical central recess placed by a force fit on said cone shaped surface, said part offering at its lower portion a cylindrical envelope surrounding said sleeve and having channels communicating with communicating channels bored in said part and in said boss for the entrance of air inside the phial, communicating channels bored in said cone shaped surface and in said part between said tapped hole and a chamber provided in said part, a pipe placed inside said chamber and leaving at the lower portion of said chamber a space for the liquid, a channel placing said chamber in communication with the outside, a cylindrical pump body having a threaded lower portion engaging in a tapped edge of said part, a vertical guiding rod extending upwards in said pump body and screwed by its lower portion in said tapped hole, a flange on said guiding rod, limiting its screwing in, an annular spring clamped by its inner edge between said flange and the upper portion of said boss, said annular spring bearing at its periphery on said part to urge said cone shaped surface of the boss into said frusto-conical central recess of said part, a piston placed inside the pump body, a piston rod, a bore in said rod allowing it to slide on said guiding rod, a cap secured to the upper portion of said piston rod, a spring interposed between said piston and the plate of said part and means for locking the upper portion of said piston rod under the bottom of the pump body when the cap is lowered to surround the latter completely.

6. An atomizer stopper according to claim 5, comprising a housing in said part, a spring inside said housing, a ball pushed by said spring, recesses placed in the upper portion of said sleeve, for yieldably holding said part with respect to said sleeve in two different rotation positions.

7. An atomizer stopper according to claim 5, comprising a recess in said part, a stud placed in said recess and two stops above the edge of said sleeve for stopping said stud in two relative positions reached by rotation of said part with respect to said sleeve.

8. An atomizer stopper according to claim 5, wherein said pipe arranged inside said chamber

5 has a vertical channel therein for expelling the air from the pump body and a fine horizontal passage located close to the bottom of said vertical channel and facing the channel going to the outside.

9. An atomizer stopper according to claim 5, comprising a lateral recess at the bottom of said chamber, a horizontal pipe inside said lateral recess, a hole at the end of said horizontal pipe 10 facing the channel which communicates with the outside.

10. An atomizer stopper for phials, comprising in combination a socket adapted to be sealed on the neck of a phial, a screw thread on the outside of said socket, a unit including a lower sleeve portion tapped to engage on said screw thread, an upper sleeve portion and a partition between said sleeve portions, said partition having a central tapped hole for receiving a capillary tube 15 dipping into the liquid in an associated phial, said partition having a chamber formed therein adjacent its periphery and a first channel extending from said central tapped hole to said chamber, a pipe disposed in said chamber and leaving a space at the bottom of the latter for the liquid, said partition having a second channel 20 communicating said chamber with the outside, a cylindrical pump body threadedly secured at its lower end in said upper sleeve portion of the unit, a vertical guide rod secured in said central tapped hole of the partition and extending upwardly from the latter into said pump body, a piston 25 slidable in said pump body, a piston rod on said piston and having a central bore to receive said guide rod, a helical compression spring interposed between said partition and said piston, a cap secured on the upper end of said piston rod and shaped to slide over the outside of said pump body, said cap having substantially the same outside configuration as said upper and lower sleeve portions of said unit, and means for immobilizing 30 said cap when the latter is pushed downwards against the action of said spring to a position abutting against said upper sleeve portion.

45 JEAN EMMANUEL PAUL TSOUDEROS.
